RECIPROCATING TRAVEL CONTROLLING MEANS

Walter S. Landon, deceased, late of Detroit, Mich.,
by Marion E. Landon, administratrix, Detroit,
Mich., assignor to Detroit Lubricator Company,
Detroit, Mich., a corporation of Michigan

Application May 15, 1947, Serial No. 748,300

16 Claims. (Cl. 74—53)

1

This invention relates to new and useful improvements in means for controlling the length of stroke of an oscillatable member or the like.

An object of the invention is to provide means for adjusting the length of stroke without altering the position to which the oscillated member returns at one end of its stroke.

Another object is to provide means by which the length of the stroke of an oscillatable member can be increased or decreased at each end of the stroke independently of change in the extent of travel at the other end of the stroke.

The invention consists in the cooperative arrangement of parts to be more fully described hereinafter and the novelty of which will be particularly pointed out and distinctly claimed.

In the accompanying drawings, to be taken as a part of this specification, there are fully and clearly illustrated a number of preferred embodiments of the invention, in which drawings,

Fig. 1 is a view in vertical section of a longitudinally reciprocal metering valve embodying the invention;

Fig. 2 is a diagrammatic view of operating mechanism for another type of metering valve also embodying the invention;

Fig. 3 is a view partly in section of a metering valve and its operating mechanism;

Fig. 4 is a view of an electrically operated and adjustable means for regulating the stroke of a reciprocal member;

Fig. 5 is a partial view in section of a reciprocating pump having means for controlling the piston travel;

Fig. 6 is a diagrammatic view of a liquid fuel burner system having a pump with automatic means for controlling the pump feed for high and low fire burner operation;

Fig. 7 is a view partly in section on the line 7—7 of Fig. 8 of a reciprocating mechanism with another form of means for adjusting the stroke of the reciprocating member, and

Fig. 8 is a top plan view of the mechanism of Fig. 7, but having the operating lever removed to show the adjusting means.

Referring to the drawings by characters of reference, in Fig. 1, the numeral 1 designates a constant level liquid chamber having a supporting bracket 2 projecting horizontally inward from the top of a side wall and having a cover member 3. The bracket 2 has a tubular guide member 4 extending therethrough and projecting upward through a cover member aperture. Above the cover member, the guide member 4 terminates in a spiral cam 5 having a low point 6 and a high

point 7 with a stop portion or member 8 therebetween which has oppositely directed vertical stop faces. The stop member 8 also provides a horizontal surface for limiting downward movement of a cam follower member 9 by engagement of a hand adjusting knob 10 therewith and which has the follower member 9 integral therewith. The follower member 9 is limited to less than a complete revolution by engagement with the stop faces of the member 8. The cover member 3 has indicia, not shown, corresponding to the cam high and low points and with which a rib pointer 11 on the knob 10 cooperates. The knob 10 has a downward extending thrust rod 12 which is guided for rotation and longitudinal reciprocation in the guide member 4. A coil spring 13 surrounds the rod 12 and is held under compression between the bracket 2 and a flange 14 on the rod 12, urging the rod 12 downward. Positioned beneath and extending transversely to the rod 12, there is an operating lever 15 fulcrumed on a shaft 16 supported by the casing 1. The lever 15 has, adjacent its free end, adjustable abutment members or screws 17, 18 which are spaced radially of each other relative to the shaft 16 and therefore longitudinally of the lever such that the screw 17 has a greater length or arc of travel than the screw 18 for a given angular displacement of the lever 15. Attached to the screws 17 and 18 are two stop discs 17^a and 18^a respectively. The angular adjustment of the screws 17 and 18 is limited to less than 360° by a stop pin 17^b which engages the stop portion of stop discs 17^a and 18^a preventing further movement. The screws 17, 18 cooperate with a plate member 19 rigidly secured to the top end of the valve stem or rod 20 of a longitudinally reciprocal metering valve having a metering slot 21 and a conical seating portion 22 cooperable with a valve seat member 23 to meter and shut off respectively the liquid flow through the outlet port formed by the seat member which is supported in an outlet conduit member 24 opening through the bottom wall of the casing 1. The valve stem 20 is guided in supporting bracket 25 and is urged up toward valve-open position by a coil spring 26 which is held under compression between the casing 1 and a cross pin 27 projecting from the stem 20. The fluid flowing through this valve enters through an inlet conduit 28 which is controlled by any standard constant level inlet valve mechanism.

In operation the valve functions as follows: When the knob 10 is turned toward open position it moves the cam follower 9 upward along the cam 5. As the cam follower 9 moves up-

ward it carries with it the knob 41 and the thrust rod 42 thus compressing the spring 43 and at the same time permitting the lever 36 to move. The valve stem 20 is urged toward open position by the spring 26 and hence is constantly bearing against the lever 36 through either or both of the screws 17 and 18. In closed position the valve stem 20 bears against the screw 17 on the lever 36. As the thrust rod 42 moves upward permitting the lever 36 to move, the valve stem 20 moves upward. This upward movement of the valve stem 20 is limited by the upward displacement of the screw against which it is bearing, and is proportional to the length of the lever arm 32 from the fulcrum 16 to the screw 17 or 18. It is obvious that the upward movement of the valve stem 20 will be greater per unit upward displacement of the thrust rod 42 when the stem is bearing against screw 17 than when it is bearing against screw 18. The valve will therefore meter greater quantities of fluid per unit change up to the point at which the valve stem 20 changes from bearing against screw 17 to bearing against screw 18. Inasmuch as the vertical travel of the thrust rod 42 is dependent upon the travel of the cam follower 9 which is limited by stop member 8 the range of movement of the lever 36 is substantially constant. The range of movement of the valve stem 20, however, is not strictly limited by the range of movement of the lever 36 since the screws 17 and 18 are adjustable. By adjustment of screw 17 which controls the amount of valve opening in valve closed position the amount of fluid metered in this position can be varied from zero to that quantity which is delivered when the screw 17 is adjusted to its maximum flow position. Similarly the screw 18 can be adjusted to vary the amount of fluid delivered in open position within the limits of adjustment by the screw.

It is obvious then that by adjustment of either or both of the screws 17 and 18 the range of fluid flow can be changed either for closed or open position and the point at which the valve changes from high delivery rate to low delivery rate (the point at which both screws are bearing against plate 19 of the valve stem 20) can be similarly changed. An additional advantage presented by the use of the adjustment screws 17 and 18 lies in the fact that the adjustment of the metering flow rate at full open and closed positions is independent of the movement of the cam follower 9 and thus does not affect the relationship of the rib 11 to the indicia on the cover member 3.

In Fig. 2 there is a valve tube or conduit 29 which conducts fluid to the metering slot 30 of a rotary valve member 31. The valve member 31 is attached to and integral with a lever arm 32 which controls the valve member movement about the fulcrum 33. Spaced longitudinally along the lever arm 32 are two adjustable abutments or screws 34 and 35 whose function is to control the range fluid metering at open and closed position and to provide a greater increment of opening from closed position as in Fig. 1. Bearing against the screws 34 and 35 is another lever 36 which is actuated by a cam 37 and which has its fulcrum 38 between the cam 37 and the screws 34 and 35. A spring 39 holds the lever 36 in compression against the cam 37 and another spring 40 urges the valve member 31 toward closed position which holds the lever arm 32 compressed against lever 36 through either or both of the screws 34 or 35. The cam 37 is actuated by a knob or dial 41 to which it is connected by a torque to rod 42.

The knob 41 is marked with suitably spaced indicia and its position indicated by a fixed indicator against which the indicia are read. For the purpose of clarity in illustration the cam 37, rod 42, knob 41, and indicator 43 are shown in perspective in approximately 90° rotation from their normal position. The dotted line view of the cam 37 which has been rotated 180° to move the valve to full open position shows the cam in its proper plane relative to the lever 36. Inasmuch as the shape of the cam 37 limits the movement of the lever 36 there is no necessity for a stop member such as member 8 in Fig. 1 and the indicia on the knob 41 are the same on each side of the initial point, thus permitting a setting to be made by either clockwise or counter-clockwise rotation of the knob.

In operation Fig. 2 is similar to Fig. 1. Movement of the knob 41 turns the cam 37 which operates the lever 36. The thrust from the lever 36 is transmitted to the valve member 31 through either or both of the screws 34 and 35 on the lever arm 32. As in Fig. 1 the screw 35 having a longer lever arm gives a greater unit increment of valve opening until screw 34 is contacted and carries the thrust to the full open position as shown in dotted lines. The same open and closed position adjustments can be made as in Fig. 1 without changing the setting of the dial 41.

In Fig. 3 there is a tapered metering valve stem 44 which is reciprocal in a metering outlet 45 and extends upward through the upper wall 46 of the valve assembly 47. A cross pin 48 holds the spring 49 in compression and the valve stem 44 is thus urged toward open position. The valve stem 44 is restrained by a lever 50 which has a fulcrum 51 and is positioned against either or both of two adjustable abutments or screws 52 and 53. The screws 52 and 53 are mounted on an actuating disc 54 which turns on an axle pin 55. The disc 54 is marked with indicia to indicate the position of the valve and is limited by two stop pins 56 and 57 which engage the indicator 58 at the limits of travel. The disc 54 is restrained from accidental movement by a friction spring 59.

In operation Fig. 3 is similar to Figs. 1 and 2. In closed position the disc 54 is turned so that stop pin 57 is engaging the indicator 58. The screw 52 is then forcing down the lever 50 and the valve stem 44 is in closed position. As the disc 54 is turned in a clockwise direction the screw 52 rises permitting the lever 50 and valve stem 44 to rise toward open position; when screw 53 takes the load from screw 52 the unit increment of valve opening is decreased as in Figs. 1 and 2. (Since the valve stem 44 is between the fulcrum 51 and the screws, the screw 53 gives a smaller unit increment of opening.) The maximum open position of the disc 54 is determined by the position of the stop pin 56. The disc 54 is restrained from accidental movement by the friction spring 59. The same metering adjustments may be made with the screws 52 and 53 as in Figs. 1 and 2.

In Fig. 4 there is a plunger 60, which could be a valve stem, a piston for a pump or the like, which extends through a wall 61. Affixed to the top of the plunger 60 is a plate 62. A spring 63 between the plate 62 and the wall 61 urges the plunger 60 upward. On the plate 62 is an abutment 64 which is restrained by a lever 65. On one end of the lever 65 is an adjustable abutment or screw 66; the other end of the lever 65 is inserted through a movable armature 67 of a solenoid coil 68. The lever 65 has a fulcrum 69

between the armature 67 and the abutment 64 and operates between the limits set by two stop pins 70 and 71. The solenoid coil 68 is energized by an electric circuit 72 containing a switch 73 which could be automatically and intermittently operable if the plunger 60 is to function as the piston of a pump.

In operation Fig. 4 differs but slightly from Figs. 1, 2 and 3. With the circuit deenergized the various parts are in position as shown in the drawing. When switch 73 is closed the circuit 72 energizes the coil 68 causing the armature 67 to move upward. The upward movement of the armature 67 carries with it the lever 65 causing it to rotate about its fulcrum 69 in a counter-clockwise direction. When the armature 67 first begins to move, the lever 65 is bearing against the abutment 64 on the plate 62. The movement of the lever 65 causes the plunger 60 to move downward compressing the spring 63. The downward movement of the plunger, as in the other figures, will be less when the thrust of the lever 63 is being carried by the abutment 64 than when carried by the screw 66. The change of lever thrust from abutment 64 to screw 66 causes the plunger 60 to have a greater increment of travel per unit displacement of the armature 67 at the downward end of its travel. As in Fig. 3 the lever 65 operates between the limits of two stop pins 70 and 71. Fig. 4 differs slightly from the others in that there is only one adjustable screw 66 and so only the length of the downstroke of the plunger 60 can be adjusted.

In Fig. 5 the device as described hereinbefore is adapted to actuate the piston or plunger of a pump. There is a longitudinally reciprocal rod or plunger 74 carried in a bore or cylinder 75. A lever 76 is operable to move the plunger 74 in a downward direction against a spring 77 which exerts an upward thrust on said plunger. The lever 76 has a fulcrum 78 and is actuated by an eccentric driving member or rotary cam 79. The thrust from lever 77 is transmitted by either or both of two adjustable abutments or screws 80 and 81 to a plate member 82 which is rigidly affixed to the plunger 78.

In operation Fig. 5 is similar to Fig. 1 with the exception that it is continuously operated. The rotation of the cam 79 forces the lever 76 downward and with it the plunger 74 causing the spring 77 to be compressed. As the cam 79 rotates past its position of maximum travel it then permits the lever 76 and the plunger 74 to rise under the thrust of the spring 77. This cycle is repeated with more or less rapidity in the continuous operation of the pump. Since the downward thrust from the lever 76 to the plate 82 is carried by the screws 80 and 81 the movement of the plunger 74 per unit movement of the lever 76 will be less when the thrust is carried by the screw 80 than when carried by screw 81. By adjustment of the screws 80 and 81 the length of the downstroke and of the upstroke of the plunger 74 can be varied as in the other applications of this principle, here giving control of pump displacement.

In Fig. 6 the basic principle as illustrated in Figs. 1 to 5 is applied to a burner control system. There is an oscillatory operated member or piston 83, preferably a longitudinally reciprocal rod, which is carried in a bore or cylinder 84. There is an inlet conduit 85 to the cylinder 84 and an outlet conduit 86 from the cylinder 84 to a burner unit 87. The flow of fluid through the cylinder 84 is controlled by an inlet check valve

88 and an outlet check valve 89. The piston 83, the cylinder 84, and the check valve 88 and 89 form the mechanism of a pump 90. Affixed to the upper end of the piston 83 is a plate member 91. A spring 92 positioned between the plate 91 and the upper face of the cylinder 84 urges the piston 83 toward an upward position. There is a rotary operating member or lever 93 which has a fulcrum 94 and terminated at one end in a yoke 95 surrounding an eccentric driving member or cam 96. The cam 96 is driven by a torque rod 97 which is connected to an electric motor 98.

There is a main circuit 99 for the motor 98 which contains a switch 100. The switch 100 may be a manual switch or a thermostatic switch which will energize the motor 98 automatically. There is a second circuit 101 which is in parallel with the motor circuit 99 between the switch 100 and the motor 98 and which includes the primary 102 of a transformer 103. A third circuit 104 includes the secondary 105 of the transformer 103, a heater element 106, and a room thermostat 107.

At the other end of the lever 93 are two adjustable abutment members or screws 108 and 109. The screw 109 in addition to being adjustable vertically is positioned in a mounting bracket 110 which pivots on a pivot pin 111 by which the bracket 110 is affixed to the lever 93. The pivotable bracket 110 has yoke arm 112 which has positioned therein one end of a bimetal thermo-responsive element 113. The other end of the bimetal element 113 is affixed to a bracket 114 by which it is mounted on the lever 93. The bimetal element 113 is responsive to the temperature of the heater element 106, which is responsive to the room thermostat 107, and is operable to move the pivotable bracket 110 and the screw 109 into and out of position as required.

In operation the system in Fig. 6 functions as follows: When the switch 100 is closed (either manually or thermostatically) the circuits 99, 101 and 104 are energized. The motor 98 upon energization begins to turn the cam 96 which causes the lever 93 to turn about the fulcrum 94 in oscillatory motion. The downstroke of the screw 108 bearing against the plate 91 causes the piston 83 to move downward. On the upstroke of the screw 108 the piston 83 moves upward being urged in this direction by the spring 92. The operation of the piston 83 by the screw 108 alone provides fuel for low-fire or pilot operation. If the room thermostat 107 is closed, calling for additional heat, the circuit 104 is completed causing the element 106 to heat. Upon heating of the element 106 the bimetal element 113 moves the screw 109 into operating position. With the screw 109 in position the lever then functions as in Figs. 1 to 5 increasing the length of the downstroke. This increase in the length of the stroke provides additional fuel for high fire operation. By adjustment of the screws 108 and 109 the length of the downstroke and of the upstroke can be adjusted as required.

It is obvious that in Figs. 2 to 6 the range of adjustment of the screws on the lever arms can be controlled by a stop disc and stop pin as in Fig. 1.

In Figs. 7 and 8 there is shown a modification of the basic principle illustrated in the preceding figures. There is a longitudinally reciprocal rod or plunger 115 having a plate member 116 on its upper end and extending through a wall 117 in which it is guided. Positioned between the plate 116 and the wall 117 is a spring 118 which urges

the plunger 115 toward an upward position. Another plate or wall member 119 is positioned above the plunger 115. There is a lever 120 having a fulcrum 121 on an abutment 122 affixed to the wall 119. Positioned between the lever 120 and the plate 116 are two abutment members or pins 123 and 124. The pins 123 and 124 extend through two curved slots 125 and 126 in the wall 119 and are positioned and guided in two pivoted supporting members 127 and 128. The pivot members 127 and 128 are pivoted on fulcrum points 129 and 130 and terminate in pointed ends which act as indicators against indicia 131 on the wall 119. The pivot members 127 and 128 have the function of adjusting the position of the pins 123 and 124 longitudinally along the lever 120. An eccentric driving member or cam 132 is positioned against the lever 120 between the fulcrum 121 and the pin 124. The cam 132 could be attached to a knob for adjustment if the device is to be used as a valve or attached to a motor or the like for continuous operation if the device should be used as a pump.

In operation the device illustrated in Figs. 7 and 8 is similar to the others with a few modifications. The spring 118 urges the plunger 115 toward an upward position and compresses the plate 116 against the lever 120, acting through either or both of pins 123 and 124. When the cam 132 is turned, it alternately forces the lever 120 downward and then permits it to rise under the thrust of the spring 118. As in the other modifications of this principle, when the lever 120 is bearing through pin 124 the rate of travel of the plunger 115 per unit displacement of the lever 120 is less than when the thrust is carried by pin 123. The essential difference between this and the other forms of the invention is that the length of downstroke and of upstroke are adjusted not by changing the length of the thrust pins but by changing their distance from the fulcrum of the lever.

What is claimed and is desired to be secured by Letters Patent of the United States is:

1. In a device of the character described, a reciprocating operated member having a variable range of movement, means movably supporting said member, a reciprocal rotary operating member having a fulcrum and a fixed range of movement, a thrust member operable to transmit movement from said operating member to said operated member, a second thrust member operable to transmit movement from said operating member to said operated member, said thrust members being spaced radially at different distances from and on the same side of the operating member fulcrum, and means to adjust the extent of movement of said operated member by one of said thrust members.

2. In a device of the character described, a reciprocating operated member having a variable range of movement, means movably supporting said member, a reciprocal rotary operating member having a fulcrum and a fixed range of movement, a thrust member operable to transmit movement from said operating member to said operated member, a second thrust member operable to transmit movement from said operating member to said operated member, said thrust members being spaced radially at different distances from and on the same side of the operating member fulcrum, and means to adjust one of said thrust members relative to said operating member thereby to change the extent of

movement of said operated member by said operating member.

3. In a device of the character described, a longitudinally movable rod, means to move said rod in one direction, lever means to move said rod in the opposite direction, thrust members spaced radially at different distances from and on the same side of the lever means fulcrum, said lever means having a fixed range of travel, one of said thrust members transmitting movement from said lever means to said rod at one end of said lever means travel, the other of said thrust members transmitting movement to said rod at the other end of said lever means travel, and means to adjust one of said thrust members to change the extent of movement imparted to said rod by said lever means.

4. In a device of the character described, a reciprocating operated member, means movably supporting said member, a reciprocal rotary operating member having a fulcrum and operable to actuate said operated member, an abutment carried by one of said members and engageable with the other of said members to transmit movement from said operating member to said operated member in one direction, a second abutment carried by one of said members and engageable with the other of said members to transmit movement from said operating member to said operated member in said one direction, said abutments being spaced radially relative to each other at one side of said fulcrum, and means to adjust one of said abutments to regulate the extent of movement of said operated member by said one abutment.

5. In a device of the character described, a controlling member, means movably supporting said member, a rotary operating member having a fulcrum and limits of movement in opposite directions, an adjustable abutment carried by one of said members and engageable with the other of said members, said abutment being adjustable to determine the position of said controlling member when said rotary member is at one limit of its movement, a second adjustable abutment carried by one of said members and engageable with the other of said members, said second abutment being adjustable to determine the position of said controlling member when said rotary member is at the other limit of its movement, said abutments being spaced radially of said rotary member for sequential engaging action.

6. In a device of the character described, an operating lever, a plunger engaging said lever, cam means having predetermined travel and operable to move said plunger, adjustable abutment screws spaced longitudinally of said lever, a longitudinally reciprocal rod, said screws being engageable with and operable to move said rod longitudinally in one direction, and resisting means to move said rod longitudinally in the opposite direction, one of said screws being adjustable to determine the movement of said rod by said lever, the other of said screws being adjustable to determine the extent of movement of said rod by said resisting means.

7. In a device of the character described, an operating lever, cam means having predetermined travel and operable to move said lever, a valve member, a lever for actuating said member, abutment screws spaced longitudinally of and secured to one of said levers, one of said screws transmitting movement between said levers at one end of the travel of said cam means, and the other of said screws transmitting move-

ment between said levers at the other end of the travel of said cam means.

8. In a device of the character described, a longitudinally reciprocal rod, a lever operable to move said rod in one direction, a spring to return said rod upon movement of said lever in the opposite direction, an eccentric driving member engaging and operable to move said lever, an abutment member transmitting movement from said lever to said rod at one end of the rod movement, and an adjustable abutment member operable to transmit movement from said lever to said rod at the other end of the rod movement.

9. In a device of the character described, a longitudinally reciprocal rod, a lever operable to move said rod in one direction, a spring to return said rod upon movement of said lever in the opposite direction, an eccentric driving member to move said lever for rod movement in said one direction, an abutment member transmitting movement from said lever to said rod at one end of the rod movement, an abutment member movable into and out of motion transmitting relation between said lever and said rod, said second-named abutment member being spaced a greater distance from the lever fulcrum than said first-named abutment member, and means to move said second-named abutment member into and out of said motion transmitting relation.

10. In a device of the character described, a longitudinally reciprocal rod, a lever operable to move said rod in one direction, a spring to return said rod upon movement of said lever in the opposite direction, an eccentric driving member to move said lever for rod movement in said one direction, an abutment member transmitting movement from said lever to said rod at one end of the rod movement, an abutment member having a pivotal support for swinging movement into and out of motion transmitting relation between said lever and said rod, said second-named abutment member being spaced a greater distance from the lever fulcrum than said first-named abutment member, a bimetal heat motor operable to swing said second-named abutment member into and out of said motion transmitting relation, and means to heat said motor.

11. In a device of the character described, an operating lever, a plunger engaging said lever, an electric solenoid coil having a predetermined travel and operable to move said plunger, a thrust member operable to transmit movement from said lever to said plunger, a second thrust member to transmit movement from said lever to said plunger, said thrust members being spaced radially at different distances from and on the same side of the fulcrum of said lever, and means to adjust one of said thrust members relative to said plunger thereby to change the extent of movement of said plunger by said electrically operated means.

12. In a device of the character described, a reciprocating member having a variable range of movement, means movably supporting said member, a reciprocal rotary operating mem-

ber having a fulcrum and a fixed range of movement, a thrust member operable to transmit movement from said operating member to said operated member, a second thrust member operable to transmit movement from said operating member to said operated member, and said thrust members being spaced radially at different distances from and on the same side of the operating member fulcrum.

13. In a device of the character described, a longitudinally movable rod, means to move said rod in one direction, lever means to move said rod in the opposite direction, thrust members spaced radially at different distances from and on the same side of the lever means fulcrum, said lever means having a fixed range of travel, one of said thrust members transmitting movement from said lever means to said rod at one end of said lever means travel, and the other of said thrust members transmitting movement to said rod at the other end of said lever means travel.

14. A device as defined in claim 12 wherein the rotary operating member is a lever, the thrust members are pins reciprocally mounted and spaced longitudinally of the lever for transmitting movement to the operated member, and including means for adjusting the longitudinal spacing of said thrust pins relative to said lever and to each other.

15. In a device of the character described, a reciprocating member having a variable range of movement, a reciprocal rotary operating member having a fulcrum and a fixed range of movement, first and second adjustable abutment members, said first abutment member engaging said operated member at one limit of its movement to determine its extent of movement in one direction, said second abutment member engaging said operated member to determine the limit of its movement in the other direction, said abutment members being independently adjustable to determine the range of movement of said operated member, and at least one of said abutment members being carried by said operating member to transmit movement from said operating member to said operated member.

16. A device as defined in claim 12 wherein there is provided a lever for transmitting movement from said operating member to said operated member, said lever engaging said operated member and being positioned for sequential engagement by said thrust members longitudinally thereof.

MARION E. LANDON.

Administratrix of Walter S. Landon, Deceased.
